UNITED STATES PATENT OFFICE.

JOHN DE LEO, OF NEW YORK, N. Y.

DESIGN FOR A TOY FLYING-MACHINE.

54,389.

Specification for Design.

Patented Feb. 10, 1920.

Application filed July 15, 1919. Serial No. 311,080. Term of patent 3½ years.

To all whom it may concern:

Be it known that I, JOHN DE LEO, a citizen of the United States, residing in the city, county, and State of New York, have invented a new, original, and ornamental Design for a Toy Flying-Machine, of which the following is a specification, reference being had to the accompanying drawing, forming a part thereof.

Figure 1 is a perspective view of a toy flying machine showing my new design, and Fig. 2 is a front elevational view thereof.

I claim:—

The ornamental design for a toy flying machine as shown.

JOHN DE LEO.
